FROZEN CONFECTION

Robert J. Betschart, Sacramento, Calif., assignor to FMC Corporation, a corporation of Delaware

Filed Nov. 16, 1964, Ser. No. 82,632

Term of patent 14 years

(Cl. D82—2)

FIG. 1

FIG. 2

FIG. 3

The essential features of the design reside in the portions shown in solid lines.

I claim:

The ornamental design for a frozen confection, as shown and described.
